Primary Examiner — Mary Ann Calabrese(74) *Attorney, Agent, or Firm* — Joseph W. Staley; Katherine D. Buchanan(57) **CLAIM**

The ornamental design for an infant support pillow, substantially as shown and described.

DESCRIPTION

FIG. 1 is a perspective view of an infant support pillow, according to the present invention.

FIG. 2 is a top view of the infant support pillow of FIG. 1; FIG. 3 is a side view of the infant support pillow of FIG. 1, the opposite side being a mirror image thereof;

FIG. 4 is a front view of the infant support pillow of FIG. 1; FIG. 5 is a back view of the infant support pillow of FIG. 1; and,

FIG. 6 is a bottom view of the infant support pillow of FIG. 1.
